Primary Examiner — Robert M Spear*Assistant Examiner* — Eliza Bennett-Hattan(74) *Attorney, Agent, or Firm* — Irina Hass(57) **CLAIM**

The ornamental design for a handle holder, as shown and described.

DESCRIPTION

FIG. 1 is a perspective view showing the new design for a handle holder;

FIG. 2 is a front view thereof;

FIG. 3 is a rear view thereof;

FIG. 4 is a left side view thereof, a right side view being a mirror image thereof;

FIG. 5 is a top view thereof; and,

FIG. 6 is a bottom view thereof.

The portions of the handle holder in FIGS. 1-6 shown in broken lines are included to show features that form no part of the claimed design.

1 Claim, 3 Drawing Sheets**US D771,476 S**
